UNITED STATES PATENT OFFICE.

HARRY S. MAYALL, OF SPOKANE, WASHINGTON.

REFRIGERANT FLUE ICE AND METHOD.

Application filed June 2, 1927. Serial No. 196,056.

The object of this invention is to provide an improved method and means for rendering ice more efficiently refrigerant, whereby either natural or artificial ice can be made 5 more efficient.

The invention also resides in the ice made in accordance with this invention, as a novel article of manufacture.

It is well known that machine refrigeration 10 can be adjusted to maintain low temperatures irrespective of the high temperature of the surrounding air and that either natural or artificial ice, as now formed or made, is strictly limited to exposure of its exterior 15 area in its effect upon air to be cooled and is therefore not susceptible of adjustment, as regards its refrigerating action.

Now it is a cardinal feature of my invention not only to increase the refrigerant capacity of cake ice but also to vary such action 20 thereof.

In one phase of my invention, I perform this function by exposing an internal portion of the ice, as well as external portions, to the 25 surrounding air or liquid in which the ice is disposed or immersed, the result being that the refrigerant action is immeasurably increased.

In a more strictly specific form of my invention, I provide a cake of ice with a series 30 or a plurality of refrigerant flues, which may be air or liquid flues, for the purpose of exposing internal portions of the ice and thereby increase the melting rate.

It is a feature of my invention to extend 35 the refrigerant flues completely through a cake of ice, preferably from one face to the other, whereby I not only succeed in exposing internal portions of the ice, but I also provide 40 channels affording actual passage of air therethrough so as to obtain an even greater refrigerant action than has heretofore been possible with solid cake ice.

If the service involves passage of air under 45 pressure, then, it is a feature of my invention to provide refrigerant air flues of a different character than if gravity passage of air is involved.

It is a feature of my invention to provide 50 means for regulating refrigeration from this novel form of cake ice in accordance with the requirements so that the melting rate may be increased or decreased as requirements dictate.

55 The invention has many other features and objects that will be more fully described in

connection with the accompanying drawing and which will be more particularly pointed out in and by the appended claims.

In the drawing;

Fig. 1, is a vertical sectional view of a conventional form of ice chest showing how my improved article of manufacture functions where the flow of air is by gravity.

Fig. 2, is a view in section showing how the 65 article functions where a forced air blast is involved.

Fig. 3, is a sectional view of mechanisms for molding ice in accordance with this invention.

Fig. 4, is a plan view of a cake of ice made 70 in accordance with my invention.

Fig. 5, is a view in side elevation of a cake of ice in which the flues do not extend completely through.

Fig. 6, is a view showing how the invention 75 is applied in forming cube ice.

Like characters of reference designate similar parts throughout the different figures of the drawing.

First describing the article shown in Figs. 1 and 4, 1 designates a cake of ice which is shown as a molded cake and which may be of any dimension in accordance with the pan or mold in which it is formed. I have shown 85 said cake provided with openings whereby internal as well as external portions may be exposed, and as specifically illustrated, said openings are in the form of refrigerant air flues 2, which extend completely through the 90 cake 1, from one external face to the other. It will be noted that the flues 2, are disposed in parallel relation and the number and size of the flues may be selected in accordance with the service to be performed.

Where gravity air flow is the service involved and the ice is called upon to function as an initiator of such flow, the showing in Fig. 1, is illustrative.

I have conventionally shown an ice chest 3, 100 of any suitable wall construction having a partition 4, dividing off the food chamber 5, from the ice chamber 6, openings 7 and 9 affording a complete cycle for the air, as shown by the arrows. An ice shelf 9, supports the 105 cake of ice 1, with the flues 2, in a vertical position, and as shown, the shelf 9 has openings through which air may freely pass. I may block the cake of ice 1, off from actual contact with shelf 9, by means such as strips 110 11, to reduce air restriction. Further, as one means of controlling the melting rate, I may

make a portion of shelf 9, imperforate, as indicated at 12, and cut off circulation through one flue when the ice cake is set directly upon the shelf. As another form of controlling 5 means, a sheet of paper or a small woolen blanket may be disposed on top of the cake to cut off circulation through any or all of the flues, as indicated at 12'.

It will now be clear that not only the outer 10 faces of cake 1, but also the flues 2, generate movement of the air through the cycle of travel indicated by the arrows. I will term this a gravity movement of the air by reason of the fact that it is because the heavier air 15 cooled by the ice, descends, and thereby causes ascent of the lighter air. The air passing downwardly through flues 2, because of the relative restriction formed thereby, will actually reach a lower temperature than the air 20 acted upon by the outside faces of cake 1, by reason of the greater volume of air upon which the latter must act. As the ice melts, the flues 2 enlarge, and instead of a cake melting to a relatively small inefficient block of 25 ice, as a slow and low capacity refrigerant agent, the cake will melt practically uniformly and comparatively quickly both externally and internally, thereby insuring the requisite low temperature in the food chamber. If a slower melting rate is desired by 30 reason of a milder condition outside, the means for regulating the melting rate may be employed, as heretofore described. It is noted that when one end of a flue 2 is covered, 35 the interior of the ice is still exposed to air that is not moving, in which event, the melting rate would be slower than if exposed to moving air. It is also within the province of my invention to equip the ice with flues or 40 openings 13, which do not extend completely through the cake, as indicated at 13, in Fig. 5. Therefore, I have shown various regulatory means for limiting the rapidity of melting, from the maximum.

45 In case the article of my invention is employed for lowering the temperature of theatres or rooms of any kind, a cake 14, may be interposed in a casing passage 15, having an air blast device 16, which is a simple and 50 general showing for such service. The ice cake 14, is supported in the casing 15 in a manner to expose the outer faces to the air blast, as shown. The cake of ice 14, will be provided with flues 17. The size of the flues 55 17 will be formed with respect to the character of the blast. With a forced blast, it will be clear that the flues need not be as large or as numerous as with a gravity air arrangement, as shown for instance in Fig. 1. Therefore, 60 with this disclosure, the skill of the maker of ice will respond to the degree and size of the flues required.

Reference will next be made to the mechanism and method for forming ice in accordance with this invention.

In Fig. 3, I have shown a brine tank 18 having a brine or suitable freezing solution 19, therein, extending to a level 20. A pan or ice mold structure is disposed in said tank in spaced relation with the walls and bottom 70 thereof, as shown, and said structure consists of a bottom wall 21, and upstanding walls 22, the latter being formed with the usual divergence. Refrigerant flue forming tubes 23, are shown threaded or otherwise detachably 75 connected with bottom wall 21, and disposed in spaced relation to each other and to the side walls 22. The tubes 23 are suitably tapered and are connected with bottom wall 21 in a manner to open into tank 18, so that the freezing solution 19 will ascend the tubes 23, to a level equal to the level 20, in the tank, or at any rate, above the ice to be formed in the mold. Water is deposited in the mold structure to a level below the level of the solution, 80 so that in freezing the water, the solution will not only act on exterior, but will also act on interior portions of the water body, thereby greatly hastening the operation of freezing the cake and also improving the quality of 85 the ice by making it of uniform density. Thus, by my improved method and mechanism, there need not be any snow in the center of the ice cake.

It will be seen that in one phase of the invention, it is an object not only to facilitate the operation of freezing a cake of ice, but to freeze the same more uniformly and with a more even density, irrespective of whether the flues or openings perform the subsequent 95 functions, as such. Thus, I may, in some embodiments, only extend the opening part way through the ice cake when the sole desideratum is to facilitate freezing. For this purpose, I have shown one tube, 23', shorter than 100 the rest, which would form an opening with a blind end. Any suitable air egress would of course be provided to let the solution ascend in such shorter tube. Thus, with a short forming tube, I would extend the action 110 of the freezing solution into the interior portions of the water body and hasten the freezing operation. That is one reason why the tubes 23 and 23' are shown detachably secured so that tubes of different character can be employed in one and the same mold to obtain ice 115 products of different character.

The invention is well adapted to and finds an advantageous use in connection with small cubes of ice that are now formed in 120 refrigerators, which feature I will next describe.

A portion of the shallow cube forming pan such as is now commonly used in refrigerators, is shown as having a bottom wall 24, 125 an end wall 25 and a partition wall 26, it being understood that these pans are divided into a plurality of cube forming chambers 27. I equip each chamber with a flue forming tube 28, that may be secured to the bottom 130

wall 24, and which may extend upwardly in the water to form a flue extending through one dimension of the ice cube. In this embodiment of the invention, instead of employing a brine or other freezing solution, the freezing agent is the cold air in the refrigerator surrounding the cube pan and acting through the thin walls thereof and the tube 28, on exterior and interior portions of the water.

When this form of cube is disposed in a glass containing any kind of a drink, the cooling action of the cube is materially enhanced by reason of the liquid flue wall acting on the contents of the glass, in addition to the outer faces of the cube, thereby hastening the melting of the cube.

It will be noted that the flues can be so equally distributed that all the intervening portions of water will be of substantially the same cross sectional area, and hence, the freezing action can be applied to not only more quickly form ice, but also, to form ice of a more uniform density. Thus, the invention not only hastens the formation of ice but it also increases its efficiency, thereby performing a dual function.

Further, ice made in accordance with my invention, is of reduced weight with respect to solid ice, which is a factor of great importance both in shipment and delivery service.

The invention affords a means whereby the flues, which function as conveyance flues, are not only of a relatively small and duct-like size, but are so relatively closely disposed and so substantially uniformly spaced and disposed throughout one cross section of the cake that a large cake of ice can be sub-divided into smaller cakes and each sub-division will have one or more flues therein intact. It will also be noted that such bores in the ice, in accordance with my invention, are not mere openings, but are conveyance flues, which perform a function analogous to the accepted definition of a flue.

It is believed that the invention will be fully understood from the foregoing descrip-

tion, and I do not wish to be limited thereby except for such limitations as the claims may 50 impart.

I claim:

1. As a new and useful article, a cake of ice having a plurality of relatively small size duct-like conveyance refrigerant flues extending therethrough and substantially uniformly distributed throughout one cross section of the cake, thereby permitting sub-division of the cake into useful sizes containing one or more flues intact in each sub-division.

2. As a new and useful article of manufacture, a cake of ice having a duct-like refrigerant flue therethrough for exposing an interior portion of the ice to increase the refrigerant action of the latter.

3. As a new and useful article of manufacture, a molded cake of ice having a plurality of duct-like refrigerant air flues molded therein and extending in parallel relation 70 from opposite faces of the cake to expose interior portions thereof to the outer air and thereby increase the refrigerant action of the ice.

4. As a new and useful article of manufacture, a molded cake of ice having a plurality of duct-like flues therein extending from different faces of the cake of ice to increase the refrigerant action of the latter.

5. In combination, a cake of ice having a plurality of flues therethrough, and means for closing one or more flues to regulate the melting rate of the ice.

6. The herein-described method of freezing a cake of ice, which consists, in confining a body of water to the size cake desired, in exposing exterior portions of the confined water to a freezing agent, and in exposing duct-like interior portions of the water to a freezing agent thereby forming a cake of ice with permanent duct-like air flues extending therethrough.

In witness whereof, I have hereby set my hand.

HARRY S. MAYALL.
